(57) **CLAIM**

The ornamental design for a card PC, as shown and described.

DESCRIPTION

FIG. 1 is an environmental view of the device with a docking station;

FIG. 2 is a top perspective view of the device in FIG. 1; FIG. 3 is a bottom perspective view of the device in FIG. 1; FIG. 4 is a top planar view of the device in FIG. 1;

FIG. 5 is a bottom planar view of the device in FIG. 1;

FIG. 6 is a left side planar view of the device in FIG. 1;

FIG. 7 is a right side planar view of the device in FIG. 1, and opposite of FIG. 6;

FIG. 8 is a front planar view of the device in FIG. 1; and, FIG. 9 is a back planar view of the device in FIG. 1.

The stipple shading is for illustrative purposes to indicate a contrast in appearance and should not be confused with surface ornamentation.

Broken lines in the drawings are included for the purpose of illustrating environmental structure only and form no part of the claimed design.
